UNITED STATES PATENT OFFICE.

CHARLES W. DAKE, OF GRAND RAPIDS, MICHIGAN.

ELASTIC-FLUID TURBINE.

No. 828,932.

Specification of Letters Patent.

Patented Aug. 21, 1908.

Application filed November 29, 1905. Serial No. 289,655.

To all whom it may concern:

Be it known that I, CHARLES W. DAKE, a citizen of the United States, residing at Grand Rapids, Michigan, have invented certain new and useful Improvements in Elastic-Fluid Turbines, of which the following is a specification.

This invention relates to improvements in elastic-fluid turbines, and particularly to the nozzle for delivering the elastic fluid to the blades or buckets of such turbines.

The objects of this invention are, first, to provide a nozzle in which the elastic fluid will be allowed to expand in its passage and discharge and preserve substantially parallel lines of movement through a rectangular nozzle; second, to provide a nozzle in which leakage or drizzle at the edges is reduced to the minimum; third, to provide a nozzle in which the delivery of the elastic fluid is substantially through the same distance from the source of supply at all points; fourth, to provide in a nozzle for elastic-fluid turbine-engines an improved adjustable valve for regulating and controlling the supply; fifth, to provide in a nozzle for turbines an improved construction of the valve to overcome leakage.

Further objects and objects relating to the details of construction will definitely appear from the detailed description to follow.

I accomplish the objects of my invention by the devices and means described in the following specification.

The invention is clearly defined, and pointed out in the claims.

A structure embodying the features of my invention is clearly illustrated in the accompanying drawings, forming a part of this specification, in which

Figure 1 is a longitudinal sectional view through the center of one of my improved nozzles and the adjoining turbine-wheel, showing the details of construction and arrangement in the preferred form. Fig. 2 is a detail side elevation view of the valve with its wedge-shaped extension. Fig. 3 is a transverse detail sectional view through the nozzle and wedge extension, taken on a line corresponding to line $x-x$ of Fig. 1 looking in the direction of the little arrows at the end of the section-line. Fig. 4 is an end view of the valve looking against the point of the wedge-

shaped extension. Fig. 5 is a detail edge view of the valve with a slightly-modified stem; and Fig. 6 is a detail longitudinal sectional view through a slight modification of my improved nozzle structure applied to a turbine having vanes or blades of the De Laval type.

In the drawings similar letters of reference refer to similar parts throughout the several views.

Referring to the lettered parts of the drawings, the nozzle consists of the casing A, the discharge-passage therefrom, A', being rectangular in cross-section and arranged at an acute angle to the side of the turbine and having a slight enlargement on the outer or longer side, whereby the side of the passage is somewhat reduced in length in the manner and for the purpose hereinafter specified. A seat N is formed at the inner end of this passage to receive the flange W of the valve.

The fluid is delivered from the channel or chamber C, which is connected to a steam-boiler or other source of supply.

The valve B has a wedge-shaped extension B' arranged within the passage of the nozzle and is provided with a flange W, which seats itself on the seat N, before referred to, for completely closing the valve. The wedge extension is cut away at B'' to form an enlargement in connection with the enlargement of the passage A'' of the casing. The point of the wedge-shaped extension is in the central longitudinal plane of the nozzle and when the valve is adjusted reciprocates back and forth in such plane.

The valve-stem is hollow in the preferred construction, appearing in Fig. 1 and is screw-threaded and extends into a sleeve D, which is screw-threaded into the nozzle-casing A. A stem G is arranged axially within this sleeve and is screw-threaded on its inner end for the purpose of controlling the valve. A collar G' is formed on this stem G. A gland E surrounds the stem, and suitable packing material H is placed under the gland. A washer I is placed next to the flange G' to keep the packing from contacting therewith, so that the stem G can be readily rotated. A hand-wheel F is provided on the outer end of the stem G for its manipulation. It is thus clear that the rotation of the hand-wheel will operate the stem, which,

through the screw on the inner end, will adjust the valve B to any desired position.

The nozzle-casing has an extended lip L at its mouth extending in proximity to the turbine-wheel to prevent leakage or spilling of the fluid between the nozzle and the wheel.

The turbine which I prefer to use is provided with buckets like those appearing in the patent to Dake and Doriker, No. 784,989, of March 14, 1905. The features of the adjustable wedge extension can be utilized with a variety of adjusting means, and I have shown a simple stuffing-box around the stem of the valve in Fig. 8. In Fig. 8 I show how the same can be applied to the side of a turbine of the De Laval type.

The arrangement of the wedge-shaped extension within the nozzle is such that the passage is divided thereby, the wedge being of a loose fit and readily adjustable. By forming the enlargement at A" the divisions or sections of the nozzles are produced in similar form. The wall of the outer part of the passage is of substantially the same length as the wall of the inner side of the wedge, and the outer side of the wedge is of substantially the same length as the inner side of the wall of the passage, so that when the valve is adjusted and the wedge extension is withdrawn or advanced the elastic fluid is delivered into the same and the outer side of the inner portion expands toward the inner side of the outer portion, meeting at the center as they pass the point of the wedge, where each tends to counteract and correct the direction of the other, so that at the outlet of the nozzle a homogeneous jet of the elastic fluid is discharged evenly in parallel lines against the buckets or vanes of a turbine in the best position and direction to be most effective. When it is desired to increase the volume of the discharge of fluid through the nozzle, the valve B, with this wedge-shaped extension, is merely withdrawn. When it is desired to reduce the volume, it is adjusted further in, and by adjusting inwardly to the limit the flange W seats itself on the seat N and entirely cuts off the flow of elastic fluid. During these adjustments the two halves of the nozzle are relatively and proportionately controlled and adjusted by the mere advance or withdrawal of the wedge-shaped extension. The outside of the nozzle-shell is provided with a lip L, which comes in close proximity to the side of the turbine and prevents or minimizes the leakage or spilling at that point.

The nozzle-passage being rectangular in cross-section, with my improved means for controlling it delivers steam or other elastic fluid in full volume into the buckets or vanes, which can be readily formed to exactly correspond to the straight lines of the rectangular sides, whereas if the cross-section of the nozzle is round more or less steam or elastic

fluid is either bound to be wasted or discharged in an ineffective manner from the nozzle to the buckets or blades.

It is obvious that any discharge from the nozzle against the outside of the vanes or buckets of the turbine will be wasted and that if the bucket or blade is unnecessarily large to embrace the whole of the cross-section of a round nozzle a part of its force will be dissipated. Hence the importance of the rectangular construction and the effective means of control thereof.

I desire to remark that many of the details of this improved nozzle structure can be varied. I have shown in Fig. 6 a modification whereby a governor or other mechanical means can be directly connected to the stem of the valve to reciprocate it. Of course in this form certain valuable features of my invention are eliminated, they being necessarily sacrificed to secure the greater facility of such regulation.

Modifications of details of this structure will no doubt readily suggest themselves to those skilled in the art to which it pertains without departing from the broad features of my invention. I desire it to be understood, however, that it is my intention to claim my invention broadly and also the specific details and features thereof.

Having thus described my invention, what I claim as new, and desire to secure by Letters Patent, is—

1. In a nozzle structure for elastic-fluid turbines, the combination of a nozzle-casing A with the nozzle-passage A' rectangular in cross-section with parallel walls, arranged to deliver therefrom obliquely against an elastic-fluid turbine-wheel, such passage being enlarged at the outer or longer side at A", and having an enlarged delivery chamber or passage C for connection to a source of supply, and provided with a valve-seat N; a valve B with a flange W arranged to seat on the valve-seat N, and provided with a wedge-shaped extension B' loosely fitting in the rectangular nozzle-passage and being cut away at B" opposite the enlargement A" in the casing, said valve having a stem screw-threaded internally; a stem G screw-threaded at its inner end within the hollow valve-stem and provided with a collar G'; a gland E embracing the stem G, with a suitable packing material H beneath the same; a washer I between the packing material and the collar G'; a hand-wheel F for controlling the stem G; a lip extension L on the outside of the nozzle-casing, arranged to extend in proximity to the face of the turbine-wheel, coacting substantially as described and for the purpose specified.

2. In a nozzle structure for elastic-fluid turbines, the combination of a nozzle-casing A with the nozzle-passage A' rectangular in cross-section with parallel walls, arranged to

- deliver therefrom obliquely against an elastic-fluid turbine-wheel, such passage being enlarged at the outer or longer side at A'', and having an enlarged delivery chamber or 5 passage C for connection to a source of supply, and provided with a valve-seat N; a valve B with a flange W arranged to seat on the valve-seat N, and provided with a wedge-shaped extension B' loosely fitting in the rectangular nozzle-passage and being cut away at B'' opposite the enlargement A'' in the casing; means for adjusting said valve; a lip extension L on the outside of the nozzle-casing, arranged to extend in proximity to the face 10 of the turbine-wheel, coacting substantially as described and for the purpose specified.
3. In a nozzle structure for elastic-fluid turbines, the combination of a nozzle-casing A with the nozzle-passage A' rectangular in cross-section with parallel walls, arranged to deliver therefrom obliquely against an elastic-fluid turbine-wheel, such passage being enlarged at the outer or longer side at A'' and having an enlarged delivery chamber or 15 passage C for connection to a source of supply, and provided with a valve-seat N; a valve B with a flange W arranged to seat on the valve-seat N, and provided with a wedge-shaped extension B' loosely fitting in the rectangular nozzle-passage and being cut away at B'' opposite the enlargement A'' in the casing, said valve having a stem screw-threaded internally; a stem G screw-threaded at its inner end within the hollow valve-stem and provided 20 with a collar G'; a gland E embracing the stem G, with a suitable packing material H beneath the same; a washer I between the packing material and the collar G'; a hand-wheel F for controlling the stem G; coacting substantially as described and for the purpose specified.
4. In a nozzle structure for elastic-fluid turbines, the combination of a nozzle-casing A with the nozzle-passage A' rectangular in cross-section with parallel walls, arranged to deliver therefrom obliquely against an elastic-fluid turbine-wheel, such passage being enlarged at the outer or longer side at A'' and having an enlarged delivery chamber or 25 passage C for connection to a source of supply, and provided with a valve-seat N; a valve B with a flange W arranged to seat on the valve-seat N, and provided with a wedge-shaped extension B' loosely fitting in the rectangular nozzle-passage and being cut away at B'' opposite the enlargement A'' in the casing; and means for adjusting said valve, coacting substantially as described and for the purpose specified.
5. In a nozzle structure for elastic-fluid turbines, the combination of a nozzle-casing, having a nozzle-passage rectangular in cross-section, with the walls thereof parallel, arranged to deliver obliquely against an elastic-fluid turbine-wheel, and having the outer 30 side enlarged and with a delivery chamber or passage connecting thereto; a valve, seated within the casing, provided with a wedge-shaped extension, the point of the wedge extending in the direction of the nozzle and intersecting the same, the outer rear portion of the wedge being cut away to correspond with the enlargement of the passage; means for adjusting the valve to regulate and control the flow of the elastic fluid, for the purpose specified.
6. In a nozzle structure for elastic-fluid turbines, the combination of a nozzle-casing, having a nozzle-passage rectangular in cross-section, with the walls thereof parallel, arranged to deliver obliquely against an elastic-fluid turbine-wheel; a valve, seated within the casing, provided with a wedge-shaped extension, the point of the wedge extending in the direction of the nozzle and intersecting the same; and means for adjusting the valve to regulate and control the flow of the elastic fluid, for the purpose specified.
7. In a nozzle for elastic-fluid turbines, the combination of a nozzle-casing with a nozzle-passage with parallel walls, arranged to deliver obliquely against an elastic-fluid turbine-wheel, and having the outer side enlarged and connecting with a delivery chamber or passage; a wedge-shaped dividing part with the point of the wedge extending in the direction of the nozzle and intersecting the same, the outer rear portion of the wedge being cut away to correspond with the enlargement of the nozzle-passage, coacting for the purpose specified.
8. In a nozzle structure for elastic-fluid turbines, the combination of a nozzle-casing, with a nozzle-passage rectangular in cross-section with parallel walls, arranged to deliver obliquely against an elastic-fluid turbine-wheel; a wedge-shaped dividing part pointing in the direction of the discharge, arranged within the passage and dividing the same and arranged to permit the elastic fluid to expand toward the center and be discharged from said passage in substantially parallel lines, for the purpose specified.
9. In a nozzle structure for elastic-fluid turbines, the combination of a nozzle-casing with a nozzle-passage leading therefrom; a valve within the said casing, said valve having a stem screw-threaded internally; a second stem screw-threaded at its inner end within the hollow valve-stem and provided with a collar; a gland embracing the said second stem outside of the collar; a suitable packing beneath the said gland; a washer between the packing and the collar; and a suitable hand-wheel for turning said second stem for adjusting the valve, coacting for the purpose specified.
10. In a nozzle structure for elastic-fluid turbines, the combination of a nozzle-casing with a nozzle-passage leading therefrom; a

valve within the said casing, said valve having
a stem screw-threaded internally; a second
stem screw-threaded at its inner end within
the hollow valve-stem and provided with a
5 collar; a gland embracing the said second stem
outside of the collar; and a suitable packing
beneath said gland, for the purpose specified.

In witness whereof I have hereunto set my
hand and seal in the presence of two wit-
nesses.
